UNITED STATES PATENT OFFICE.

WILLIAM F. KRULL, OF SPRINGFIELD, OHIO.

CLOTHES-SUPPORT.

SPECIFICATION forming part of Letters Patent No. 341,022, dated May 4, 1886.

Application filed December 17, 1884. Serial No. 150,566. (No model.)

To all whom it may concern:

Be it known that I, WILLIAM F. KRULL, a citizen of the United States, residing at Springfield, in the county of Clark and State of Ohio, 5 have invented certain new and useful Improvements in Clothes-Supports, of which the following is a specification, reference being had to the accompanying drawings.

This invention relates to certain improvements in supports upon which to hang articles of wearing apparel; and it has for its objects to provide a compact and convenient device upon which the articles may be placed, and in such a manner as to hang in a position that 15 will preserve their shape, as more fully hereinafter set forth. These objects I attain by the means illustrated in the accompanying drawings, in which—

Figure 1 represents a perspective view of 20 my improved device entire. Fig. 2 represents a cross-section taken on the line $y-y$ of Fig. 1, and Fig. 3 a cross-section taken on the line $x-x$ of Fig. 1. Fig. 4 represents a sectional view of a portion of the device, showing the latch mechanism.

The letter A indicates a rod or shaft, which is preferably cylindrical in cross-section, and which may be constructed of any suitable material. The upper end of said rod is provided 30 with a hook, B, by which it may be suspended, and just below said hook with a loosely or rigidly fitted cross-plate, C. The said plate at its ends is provided with downwardly-extending flanges C', and below said flanges are hinged 35 the upper ends of two curved wings, D, shaped to conform to the shoulders of a person.

The letters D' D' indicate the wings of the hinge, to which the wings D are attached; and D', plates secured to the under side of the plate 40 C, forming the central portion of the hinge, to which the wings D' are pivoted at d. The office of the flanges C' is to cover the upper edges of the wings D, and prevent them from coming in contact with the garment, and prevent them 45 from rising too high, and also to give a neat finish to the device. These wings, underneath and near their outer ends, are provided with cross-wires E, to which are pivoted the outer ends of the braces F, the inner ends of which 50 are pivoted to the head of the sleeve G, adapt-

ed to slide upon the shaft or bar. The said shaft or bar is provided with an umbrella-latch, H, which is adapted to set through the slot K in the sleeve and hold the arms in an elevated position. The latch K is provided 55 with an extension below its bend, which extension is bent outwardly, forming a stop, L, which projects normally outward and holds the sleeve, to prevent downward movement when it is elevated.

The lower end of the rod or shaft is provided with an eye, M, to which may be secured the hook N of a short rod, P. The said rod is provided with longitudinally-flanged arms R, extending diametrically to opposite sides of the 65 same, in which are adapted to slide similarly-flanged arms T, which are slotted longitudinally and carry the sliding arms U, which have curved heads V at their outer ends and adjusting clamping-nuts W, which can be clamped 70 upon the arms T, so as to bind the parts. The lower rod is also provided with a disk, Y, from which extend diametrically in four directions the upwardly-inclined springs Z, to which are attached the suspended straps A', which have 75 at their lower ends the eye-loops B', as shown.

To use my improved device, the upper shaft is suspended from any suitable support, and the wings being raised or elevated the upper garment or coat may be placed upon the same 80 and supported thereby in a natural position. The lower shaft may be attached, as above described, to the upper shaft, and the lower garment or pantaloons supported thereon, the curved outer ends of the adjustable radial rods 85 being pushed in or out, so as to keep the upper parts of the pantaloons materially distended, while the dependent straps, by means of the button-loops, will serve as a support to the pants, the loops being secured over the buttons. 90

It is evident that the parts may be used separately or together without departing from the spirit of my invention.

By hinging the wings D they may be let down or folded against the handle when not in use, 95 to render the device more compact for transportation or storage.

The stop L is in such position as to engage the lower edge of the sleeve G when the parts are fully distended and hold them in position. 100

Having thus described my invention, what I claim, and desire to secure by Letters Patent, is—

1. The combination, with the vertical shaft or rod provided with a hook at its upper end, of the pivoted wings, the braces and sliding sleeve, and latch device, to form a support for a garment, substantially as described, and for the purposes set forth.
2. The combination, with the upper rod or

shaft and its adjustable wings, of the lower shaft or rod and its adjustable arms and supporting-straps, all arranged substantially as and for the purposes described.

In testimony whereof I affix my signature in presence of two witnesses.

WILLIAM F. KRULL.
